ORREN A. SAWYER, OF LOWELL, MASSACHUSETTS.

WEFT-FORK ACTUATOR FOR LOOMS.

1,067,941.

Specification of Letters Patent. Patented July 22, 1913.

Application filed July 8, 1912. Serial No. 707,457.

To all whom it may concern:

Be it known that I, ORREN A. SAWYER, a citizen of the United States, residing at Lowell, in the county of Middlesex and Commonwealth of Massachusetts, have invented 5 a certain new and useful Improvement in Weft-Fork Actuators for Looms, of which the following is a specification.

This invention relates to weft-fork-actuators for looms, in which a stop-motion on 10 weft-replenishing devices is controlled by such a fork and a rack and involves supporting the rack independently of the lay and making the rack movable synchronously 15 with the beating up of the lay in such a manner that the bars of the rack will always register with the spaces between the tines of the fork.

In most common plain looms for weaving 20 cotton or woolen goods there is a stop-motion which is prevented from operation by the presence of an unbroken weft or filling thread between the shuttle in the shuttle-box and the cloth and in many weft-replenishing looms the weft-supplying mechanism is similarly prevented from operation. In 25 each case, a weft-fork is pivoted on a slide which is supported on the breast-beam and said fork is provided at its front end with 30 a hook, the office of which is to engage a vibrating arm of a rock-shaft and to cause the slide which supports said weft-fork to be moved to release or actuate the devices which shift the belt or otherwise stop the 35 loom, or which introduce a new supply of filling. The lay-beam of such a loom, as hitherto constructed, is provided between the reed and one of the shuttle-boxes with a rack or plurality of vertical bars and the 40 rear end of the weft-fork is bent down and divided into tines, each intended to pass through one of the spaces of the rack in the absence of a weft-thread, but when a weft-thread is held in front of the rack, the 45 tines or fingers of said fork are pushed forward by the forward swing or beating up of the lay, tilting the front end of the fork out of the path of the vibrating arm and preventing the loom-stopping or weft-changing 50 operation from taking place. The spaces between the bars of the rack on the one hand, or between the tines of the fork, on the other, are made quite narrow in order that the friction of the yarn on these bars and 55 tines may be sufficient to prevent the yarn from simply looping back and forth between

said bars and tines without tilting the lever, the tension of the yarn in the shuttle being very slight, and the yarn between the shuttle (when in the box) and the reed being 60 frequently loosened by the rebound of the shuttle in the box, so that the tension of the yarn is insufficient to tilt the fork. Lint gathers on the rack or fork or on both and causes the fork to be tilted after the weft is exhausted or broken. When the weft-fork continues to be tilted after the breaking or exhaustion of the filling, the loom continues to run and makes a thin place in the cloth. It is necessary that the weft-fork 65 should be carefully set and prevented from lateral movement on its fulcrum, in order that the tines of the fork may not be hit by the rack and tilted in the absence of the filling, and also in order that the tines of 70 the fork may not be broken, battered or bent by contact with the rack. Sometimes the tines are so bent laterally that the fork is tilted by the rack, in the absence of filling. Frequently the fork is caused to strike the 75 rack by the lay shifting position laterally in its bearings. Sometimes the wear of the pitman connections, the straps and boxes which connect the pitman to the lay, and the crank shaft become so worn as to allow the 80 lay to swing too far forward in beating up, so that the bars of the rack strike the closed ends of the spaces between the tines of the fork and tilt the fork in the absence of filling. Sometimes a training end of exhausted or broken filling will continue to tilt 85 the fork making a thin place. The lint which gathers on the rack and on the fork is frequently carried into the cloth, making "thick places" or bunches. 90

By the improvement hereinafter described, I obviate the difficulties above mentioned. I accomplish this by supporting the rack upon a pivot in such a manner that the bars of the rack always register with the 100 spaces between the tines of the weft-fork, and the rack enters the fork at every pick, clearing the fork and rack of lint and loosening the trailing thread and looping said trailing end into both the fork and rack in 105 such a manner that it can tilt the fork but once.

In the accompanying drawing, on two sheets, Figure 1, is a right side elevation of a part of a loom showing the weft-hammer, 110 its actuating cam, the weft-fork, its slide and stand, the tilting rack, the spring-pusher

supported on the sword of the lay, and in vertical section the lay beam and reed-cap; Fig. 2, a front elevation of parts of the frame, breast-beam, lay-beam, reed, reed-cap, weft-fork, stand and spring-pusher; Fig. 3, a right side elevation of the rack, weft-fork, its stand and slide, and the upper part of the weft-hammer, the fork and rack being shown in full lines in their untilted positions, in dotted lines in the positions they occupy when tilted; Fig. 4, a rear elevation of the weft-fork and rack with a weft-thread between them; Fig. 5, a right side elevation of the weft-fork and rack; Fig. 6, a plan of the slide, weft-fork, rack, spring-pusher and lay-beam, and a horizontal section on line 6—6, in Fig. 5 of a sword of the lay; Fig. 7, similar to Fig. 4, but omitting the weft-thread and showing a slight modification of the fork and rack.

A, indicates a loom-side or part of the loom-frame; B, the cam-shaft; b, the weft-hammer operating cam; C, the weft-hammer, the same being a bent-lever, the lower end *c*¹ of which rests upon the cam *b*, said weft-hammer being fulcrumed at *c*¹ and its upper end *c*² being swung forward by the lifting of its lower end by the cam *b*, and returned by gravity; D, the weft-fork which is a bent lever fulcrumed at *d* in the slide E, and having a hook *d*¹ to be engaged by the upper end *c*² of the weft-hammer when the filling is broken or exhausted, and to be drawn forward carrying with it said slide; F, the stand, on which the slide moves; A¹, the breast-beam; G, the lay-beam; g¹, the lay-swords; g², the reed-cap; and H, the reed; all these parts being of the usual construction and operation, except as herein-40 after stated, and the slide being connected by intermediate mechanism with a belt-shipping lever or other device which shuts off the power from the loom when the slide is drawn forward.

45 The rack, I, instead of being merely a series of bars arranged in a common plane and carried by the lay in the usual manner, is here represented as similar in form to the weft-fork D and pivoted at *i*, in the same 50 slide E in the rear of the fulcrum *d* of said weft-fork (Figs. 3 and 5) in such a manner that the tines or bars *i*¹ when swung forward will register with the spaces between the tines *d*² of the weft-fork, the fulcrums 55 or hubs of said weft-fork and rack being parallel with each other and both turning in the parallel sides *e* *e*¹ of the slide E. The rack is nearly straight (but has a downwardly curved offset immediately back of its 60 hub, as hereinafter mentioned) and its front end is weighted at *e*², and normally rests upon a stop-stud *i*² which projects horizontally from an inner wall of the slide E, (Fig. 3), so that the rear or forked arm of 65 the rack is normally in a nearly horizontal

position as represented by full lines in Fig. 3, so that when the lay beats up, the weft or filling thread carried by the lay, passes first under said forked arm of said rack. When the lay has almost completed its forward movement the front end of a spring-pusher *J*, strikes upon the top of a backwardly and downwardly curved offset portion *i*³ of the rear arm or rack proper and depresses it into the position shown by dotted lines in Fig. 3, carrying the filling thread against the back of the weft-fork, and tilting said weft-fork and raising its hook out of the path of the upper end of the weft-hammer so that the slide is not moved and the stop-motion or filling changing devices are not operated. The operative movement of the rack is limited by a radial projection *i*⁴ on the hub *i*⁵ of said rack striking the under side of the stop-stud *i*² above mentioned.

In Fig. 4, the lower free ends of the tines *d*² of the weft-fork are represented as connected by a cross-bar *d*³ which serves to stiffen said tines and to preserve the spaces between said tines and furnishes an additional precaution against the interference of said tines with the bars of the rack.

The spring-pusher *J* is represented as a flat-sided rod *j* sliding in a bearing *j*¹ supported on a bracket *j*³ carried by the sword *g* of the lay and forced forward by a spring *j*⁴ surrounding said rod and compressed between the head *j*⁵ or enlarged front end of said pusher, and said bracket *j*³, the shape of said rod and its bearing preventing the 100 rod from turning and the spring being of sufficient strength to tilt the rack but sufficiently yielding to avoid breaking or bending the rack after the projection *i*⁴ is in contact with the stop-stud *i*².

In Fig. 7, the outer tines only of the fork are represented as joined by the bar *d*³ and the free ends of the bars of the rack are joined by a cross-bar *i*⁶ to stiffen and strengthen said bars and the middle tine of 110 the fork is cut away to allow said cross-bar *i*⁶ to pass under it.

I claim as my invention—

1. The combination in a loom of a weft-fork, a pivoted rack, the bars of which are arranged to register with the spaces between the tines of said fork, and means carried by the lay for swinging said rack into said fork at each pick of the loom.

2. The combination in a loom of a weft-fork, a pivoted rack, the bars of which are arranged to register with the spaces between the tines of said fork, and means for swinging said rack into said fork by the forward movement of the lay.

3. The combination in a loom of a weft-fork, a pivoted rack, the bars of which are arranged to register with the spaces between the tines of said fork, and yielding means carried by the lay and adapted to engage 130

said rack and to swing said rack into said fork.

4. The combination in a loom of a weft-fork slide, a weft-fork, a rack, said rack and fork turning on parallel pivots in said slide and the bars of said rack being arranged to register with the spaces between the tines of said fork and means carried by the lay for swinging said rack into said fork.
- 10 5. The combination in a loom, of a pivoted weft-fork, a pivoted rack, the bars of which are arranged to register with the spaces between the tines of said fork, a stop to limit the swinging of said rack into said fork, and a spring-pusher carried by the lay
- 15

and adapted to yield when said rack is in contact with said stop.

6. The combination in a loom, of a pivoted weft-fork having the outer ends of its tines connected by a cross-bar to stiffen the 20 same, and a pivoted rack having bars arranged to register with the spaces between said tines, and means carried by the lay for swinging said rack into said fork.

In witness whereof, I have affixed my signature, in presence of two witnesses.

ORREN A. SAWYER.
